(57) **CLAIM**

The ornamental design for bottom garment with double stitching, as shown and described.

DESCRIPTION

FIG. 1 is a rear view of the first embodiment of my new design for a bottom garment with double stitching design; and,

FIG. 2 is a rear view of the second embodiment of my new design for a bottom garment with double stitching design.

The dashed lines on the surface of the garment represent stitching. The remaining dot-dot-dashed lines represent the portions of the design, which form no part of the claim.

1 Claim, 1 Drawing Sheet

FIG. 1

FIG. 2
